CLAIM

The ornamental design for a support pedestal for a table, as shown and described.

DESCRIPTION

FIG. 1 is a perspective view of a furniture pedestal,
showing my new design;

FIG. 2 is a top plan view;

FIG. 3 is a side elevational view;

FIG. 4 is an alternate side elevational view;

FIG. 5 is a perspective view of a furniture pedestal,

showing a second embodiment of my new design;

FIG. 6 is a top plan view of the second embodiment;

and

FIG. 7 is a side elevational view of the second embodiment,

the opposite side being a mirror image thereof.

FIG. 7
